UNITED STATES PATENT OFFICE.

PHILIP MUELLER, OF DECATUR, ILLINOIS, ASSIGNOR TO ADOLPH MUELLER, TRUSTEE, OF DECATUR, ILLINOIS.

BATH AND SHOWER COMBINATION.

Application filed October 19, 1925. Serial No. 63,522.

The present invention relates to lavatory fittings, and more particularly to a combination faucet and shower structure including a curtain support.

5 An object of the invention is to provide a structure of pleasing appearance, which may be readily positioned and is adaptable for use, either with an overhead shower or a flexible spray tube, having its nozzle positioned conveniently for manual operation.

10 A further object of the invention is to combine with a shower and faucet structure a rigid curtain support, which is at least partially carried by the shower proper.

15 Other objects of the invention have to do with the details of construction of the curtain support and shower, and will become more apparent as the description proceeds in connection with a preferred embodiment 20 of the invention shown in the accompanying drawings, wherein:

Figure 1 is an elevational view,

Figure 2 is a detail view showing the spray tube connection.

25 Figure 3 is a vertical sectional view indicating the construction at the junction of the curtain ring support and the shower column.

Figure 4 is a vertical section on the line 30 4-4 of Figure 3, and

Figure 5 is a horizontal section showing the support for the opposite end of the curtain ring.

Referring to the drawings for a more detailed description, 10 indicates a faucet having hot and cold water cocks 11, 12, a central mixing chamber 13, and a switch valve 14 adapted to direct the flow either through a spout 15 or nipple 16, leading to a suitable shower column 17. The fixture is shown as positioned within a tub, the outline of which is diagrammatically indicated, and the shower column 17 is connected to the nipple 16, as by means of a socket 18, at the end of the nipple, which receives an extension 19 upon the end of the collar, the latter having an orifice within the socket to permit the water to enter the column. A suitable stud 20 passes through the extension 19 and the socket member to provide a pivotal connection, whereby the column may be adjusted to a horizontal axis to obtain the desired vertical position. The column 17, which is preferably a rigid pipe may be formed in two sections united by a coupling 21, which has a

lateral passage 22 directed through an extension 23, the latter being formed with a nipple 24 for the spray tube 25, and if desired, there may be positioned upon the extension a saddle member 26, upon which the tube may be supported when not in use.

The shower column extends upwardly to a junction member 27, which is preferably spherical and has an aperture 28 to receive the threaded end 29 of the column. The junction member is supported by means of one or more bracket arms 30, which may be of telescopic construction to permit their extension to an adjacent supporting wall. A suitable construction is indicated in the drawings, in which sections 31 have threaded extremities 32 engaging internal threading 33 in larger sections 34, the ends of the latter fitting into sockets 35 in the junction member 27. The smaller sections 31 have their free ends secured in bracket plates 36, which carry toggle bolts 37 serving as attachment means for mounting the brackets in position upon a suitable supporting wall W.

It will be noted that the bracket arms 30 extend outwardly from the junction member at right angles to one another, so as to hold the shower column rigidly in position. The junction member also serves to carry a suitable curtain support, in the present instance in the form of a ring 38, which comprises two substantially semi-circular sections, the ends 39 of which are held in sockets 40 of the junction member 27 by means of lock collars 41 fitted upon the slightly flanged ends of the ring and having a threaded engagement with the sockets 40. If desired, the sections of the ring may be completely separated to form two substantially semi-circular sections supported at their other ends, as indicated in Figure 5, by means of a spherical junction member 42, having lateral sockets 43 receiving the ends 39' of the ring sections, the latter being held therein by collars 44. The junction member 42 is supported in the same manner as the member 27 by one or more extensible bracket arms 44 projecting toward the adjacent wall and secured thereto, as by a toggle bolt connection 45.

105 The device is adaptable for use as an overhead shower, it being noted that the junction member 27 is hollow (Figure 4), the opening 28 which receives the shower column communicating with a lateral orifice 48, which 110

may, when used with a spray tube, as in Figure 1, be closed by a plug 50. The ori-
fice 48, however, is adapted to receive a
shower head when the plug is removed, and
as will be understood, in such cases it is
simply necessary to substitute for the cou-
pling 41, an ordinary coupling to permit the
water to rise to the shower head, which may
be substituted for the plug 50.

10 When the structure is assembled, it will be
understood that the faucet proper is first
positioned, and the shower column 17 is then
suitably connected thereto, the brackets 30
15 at the upper end thereof which carry the
junction plug 27 being adjusted to reach the
adjacent wall and ceiling to the end of the
column. If the spray tube 25 is to be em-
ployed, the precise structure shown in Fig-
ure 2 may be used to connect the sections of
20 the shower column, but if an overhead shower
is preferred, an ordinary coupling permit-
ting the ascent of the water in the column
may be substituted therefor. It will be
noted that the brackets 30, 44 rigidly carry
25 the curtain ring, as well as the shower col-
umn. The adjustment of the shower column
at the joint 20 permits the alignment of the
same with the junction member 27 at the
upper end thereof and the possible adjust-
30 ment of the bracket arms 30 affords a com-
plete structure which may be readily as-
sembled and installed for use.

In the operation of the device, the hot and
cold water cocks 11, 12 may be turned to
35 proper position to cause the flow of water of
the desired temperature and force, and by
means of the switch cock 14 the water may
be directed through the spout 15 until the
shower is to be employed, whereupon actua-
40 tion of the switch valve 14 will direct the
water either through the spray tube 25, or,
if an overhead shower is employed, through
the shower head.

45 It should be understood, of course, that the
invention is not limited to the precise details
of construction illustrated and described, but
that such modifications may be made therein
as come within the scope of the following
50 claims.

I claim:

1. A faucet and shower combination com-
prising the combination with hot and cold
water valves and connections therefor, of a
55 mixing chamber structure between said
valves, a supply spout leading from said
chamber, a rigid shower column leading up-
wardly from said chamber, a switch valve in
said chamber for controlling the discharge
60 through said spout and shower column, and
means connecting said column to said cham-
ber structure permitting adjustment of said
column about a horizontal axis relative to
said chamber.

65 2. A faucet and shower combination com-
prising the combination with hot and cold

water valves and connections therefor, of a
mixing chamber structure between said
valves, a supply spout leading from said
chamber, a rigid shower column leading up-
wardly from said chamber, a switch valve 70
in said chamber for controlling the discharge
through said spout and shower column, said
column having a shower outlet, and means
for securing the upper end of said column
and supporting therefrom a curtain ring, 75
said means comprising a junction member
adapted to receive the column, an arm re-
ceived in a socket in said member and ex-
tending outwardly therefrom and adapted
to be secured to a rigid support, said member
80 having sockets to receive the ends of the sec-
tions of a curtain ring.

3. A faucet and shower combination com-
prising the combination with hot and cold
water valves and connections therefor, of a 85
mixing chamber structure between said
valves, a supply spout leading from said
chamber, a rigid shower column leading up-
wardly from said chamber, a switch valve
associated with said chamber for controlling
90 the discharge through said spout and shower
column, said column having a shower outlet,
means for securing the upper end of said
column and supporting therefrom a curtain
ring, said means comprising a junction mem-
95 ber adapted to receive the column, an arm ex-
tending outwardly from said member and
adapted to be secured to a rigid support, said
member having sockets to receive the ends of
the sections of a curtain ring and an open-
100 ing in communication with said column serv-
ing for the attachment of a shower head.

4. A device of the class described com-
prising the combination with hot and cold
water valves and connections therefor, of a 105
mixing chamber, a shower column leading
from said chamber, a junction member at the
upper end of said column and receiving the
latter, a bracket arm carried directly by said
member and extending outwardly therefrom
110 and carrying means for securing the same to
a rigid support, said member having sockets
to receive the ends of curtain ring sections,
and a curtain ring formed in sections with
their ends fitted into said member.

5. A device of the class described com-
prising the combination with hot and cold
water valves and connections therefor, of a
mixing chamber, a shower column leading
120 from said chamber, a hollow junction mem-
ber at the upper end of said column and re-
ceiving the latter, an outlet opening in said
member serving for the attachment of a
shower head, a bracket arm extending out-
wardly directly from said member and car-
rying means for securing the same to a rigid
support, said member having sockets to re-
ceive the ends of curtain ring sections, and a
curtain ring formed in sections with their
ends fitted into said member.

6. A device of the class described comprising the combination with hot and cold water valves and connections therefor, of a mixing chamber, a shower column leading from said chamber, a junction block at the upper end of said column and receiving the latter, bracket arms fitted into sockets in said block and extending outwardly therefrom at right angles to one another and carrying means for attachment to a rigid support, said block having sockets to receive the ends of curtain ring sections, and a curtain ring formed in sections with their ends fitting into said block. 55
- 10 7. A device of the class described comprising the combination with hot and cold water valves and connections therefor, of a mixing chamber, a shower column leading from said chamber, a hollow junction block at the upper end of said column and receiving the latter, an outlet opening in said block serving for attachment of a shower head, bracket arms extending outwardly from said block at right angles to one another and carrying means for securing the same to a rigid support, said block having sockets to receive the ends of curtain ring sections, and a curtain ring formed in sections with their ends fitted into said block. 70
- 15 8. A curtain ring and support therefor comprising junction members, bracket arms extending outwardly from said members and having means serving for attachment to a rigid support, each junction member having lateral sockets, and curtain ring sections having their ends fitting into said sockets, one of said members being hollow and having an opening to receive the end of a shower column and an additional opening to receive a shower head. 75
- 20 9. A curtain ring and support therefor comprising a pair of junction members each having sockets on opposite sides thereof, curtain ring sections having their ends fitting into said sockets, additional sockets in said members to receive the ends of bracket arms, and bracket arms fitting into the last mentioned sockets and extending outwardly from each of said members substantially at right angles to one another, said arms having at their ends means for attachment to a rigid support. 80
- 25 10. A curtain ring and support therefor comprising a pair of junction members each having sockets on opposite sides thereof, curtain ring sections having their ends fitting into said sockets, additional sockets in each of said members to receive the ends of bracket arms, bracket arms fitting into said sockets and having at their free ends means for attachment to a rigid support, there being two arms for each member positioned at right angles to one another. 85
- 30 11. A curtain ring and support therefor comprising a pair of junction members each having sockets on opposite sides thereof, curtain ring sections having their ends fitting into said sockets, additional sockets in each of said members to receive the ends of bracket arms, and extensible bracket arms fitting into said sockets and having at their free ends means for attachment to a rigid support, there being two arms for each member positioned at right angles to one another. 90
- 35 12. A curtain ring and support therefor comprising a pair of junction members each having sockets on opposite sides thereof, curtain ring sections having their ends fitting into said sockets, additional sockets in said members to receive the ends of bracket arms, bracket arms fitting into said sockets and having at their ends means for attachment to a rigid support, one of said members having a passage therethrough, and a vertical shower column fitting into one end of said passage, the other end thereof being adapted to receive a shower head. 95
- 40 13. A curtain ring and support therefor comprising a pair of junction members each having sockets on opposite sides thereof, curtain ring sections having their ends fitting into said sockets, additional sockets in each of said members to receive the ends of bracket arms, bracket arms fitting into said sockets and having at their free ends means for attachment to a rigid support, there being two arms for each member positioned at right angles to one another, one of said members having a passage therethrough, and a vertical shower column fitting into one end of said passage, another end thereof being adapted to receive a shower head. 100

In testimony whereof I have hereunto set my hand.

PHILIP MUELLER.
